Patented Oct. 31, 1916.

UNITED STATES PATENT OFFICE.

ERNEST M. WHITE, OF DETROIT, MICHIGAN.

LUBRICANT-CONTROLLING MECHANISM.

1,202,938.

Specification of Letters Patent. Patented Oct. 31, 1916.

Application filed June 8, 1916. Serial No. 102,415.

To all whom it may concern:

Be it known that I, ERNEST M. WHITE, a citizen of the United States, and residing at Detroit, in the county of Wayne and State 5 of Michigan, have invented a new and Improved Lubricant-Controlling Mechanism, of which the following is a specification.

This invention relates to means for conveying the excess of lubricating oil from the 10 crank case of an internal combustion engine to the main oil receptacle, and its object is to provide a device of this character which shall be simple and effective, and which can be constructed at low cost.

15 This invention consists of a conduit extending to the main oil reservoir of an internal combustion engine from a point intermediate two auxiliary receptacles in which is held the oil into which dip the 20 lower ends of the connecting rods to splash the lubricant up into the cylinder in order to lubricate the pistons.

This invention further consists in providing this conduit with a check-valve which 25 prevents the flow of the lubricant from the main oil reservoir when the vehicle is going down hill.

In the accompanying drawing, Figure 1 is a view, partly in elevation and partly in 30 section, of an internal combustion engine provided with this present invention. Fig. 2 is a plan of the discharge end of the conduit. Fig. 3 is a transverse vertical section through the intake end thereof.

35 Similar reference characters refer to like parts throughout the several views.

The engine shown in Fig. 1 consisting of the cylinders 1, upper crank-case 2 having an extension 3 in which the fly-wheel and 40 magneto are mounted, lower crank-case 4 having an extension 5 which constitutes the main oil reservoir, the crank shaft 6, cranks 7, 8, 9, 10 and 11 (the other not being shown), connecting rods 13 and 14 (the 45 other two not being shown), the removable bottom 15 of the lower crank-case provided with auxiliary oil receptacles and held in position by means of the screws 16, and the bar 17 that extends around the opening in 50 the lower crank-case and acts as a reinforcement, is of well known construction, being that of the present Ford automobile.

The lubricant may be conveyed from the main oil reservoir to the opposite end of the 55 crank-case in any desired manner, the usual means being a tube 19 having a funnel 20

that catches oil splashed up by the fly-wheel and magneto. When the vehicle is going up hill, the lubricant flows back over the rear transverse portion 21 of the reinforcing bar and while the depth of oil in the rear receptacle 22 is somewhat deeper than necessary, the excessive amount splashed up is not very objectionable. But when the vehicle is going down hill, the lubricant collects in the front end of the crank case until it is quite deep in the front receptacle 24, so much so that the amount of oil splashed up into the front cylinders is so large that the 60 spark-plugs, cylinders and the passages thereto become thickly coated with carbon from the burnt oil. In order to remove this excess of oil, I attach a connection 25, preferably in the form of an elbow, to the bottom 15 and connect a pipe 26 on this elbow. 65 A nipple 27 screws into a threaded hole in the wall 28 forming a part of the main reservoir, which hole normally receives a cock or gage to determine the height of liquid in the reservoir, and a check-valve 29 is preferably placed between this nipple and the rear end of the pipe 26. This valve will preferably connect to the T 30 which can also support the depth gage 31. The valve and 70 depth gage may be omitted if desired. 75

When the vehicle is moving over level roads, the bottom 15 should be level and the excess of lubricant will be drained off by means of the pipe 26. The result is that the receptacles 22-23-24 will contain just 80 the desired amount of oil and the quantity splashed up will not be substantially greater or less than required by the moving parts of the engine. Experience has shown that it is practically impossible to regulate the feed 85 of lubricating oil to the receptacles 22-23-24 through the pipe 26, for the conduit that will carry sufficient oil under certain conditions will convey either more or less than enough under other conditions. As a result, means to take care of the excessive delivery are of great advantage. The present device can be attached to hundreds of thousands of vehicles now in use without 90 changing any of the present constructions. 105

I claim:

1. In an internal combustion engine, the combination of a crank-case formed with a main oil reservoir and having a bottom provided with auxiliary receptacles from which 110 the lower ends of the connecting rods may splash lubricating oil, and a conduit

- tending from said bottom between two of the receptacles to the main reservoir.
2. In an internal combustion engine, the combination of a crank-case formed with a main oil reservoir and having a bottom provided with auxiliary receptacles from which the lower ends of the connecting rods may splash lubricating oil, a conduit extending from said bottom between two of the receptacles to the main reservoir to convey oil from the crank case to said reservoir, and means to prevent the return flow of the oil.
3. In an internal combustion engine, the combination of a crank case formed with a main lubricating-oil reservoir at one end and having a flat removable bottom provided with depressions adapted to serve as auxiliary reservoirs for the lubricating oil, an elbow connected to said bottom between the two receptacles farthest from the main reservoir, a downwardly inclined pipe extending to the main reservoir, and a check-valve connected to the main reservoir and to said pipe to permit the flow of oil to the main receptacle and prevent the return flow of the oil.
4. In an internal combustion engine, the combination of a crank case formed with a main lubricating oil reservoir at one end and having a flat removable bottom provided with depressions adapted to serve as auxiliary receptacles for the lubricating oil, a reinforcing bar extending around the edge of the removable bottom and adapted to normally confine a pool of oil, a fitting connected to said bottom between auxiliary receptacles, and a conduit extending from said fitting to an opening in the wall of the main oil reservoir.
5. In an internal combustion engine, the combination of a crank case formed with a main lubricating oil reservoir at one end and having a flat removable bottom provided with depressions adapted to serve as auxiliary receptacles for the lubricating oil, a reinforcing bar extending around the edge of the removable bottom and adapted to normally confine a pool of oil, a fitting connected to said bottom between auxiliary receptacles, and a conduit extending from said fitting to an opening in the wall of the main oil reservoir.
